UNITED STATES PATENT OFFICE

CHARLES H. SUCKEL, OF JACKSON HEIGHTS, NEW YORK

AUTOMATIC SASH FASTENER

Application filed October 14, 1929. Serial No. 399,554.

This invention relates to closure fasteners and more particularly to a novel window sash fastener.

One of the primary objects of my invention is to provide a fastener which will automatically lock the sashes together, when the same are moved to their extreme closed position, thereby insuring of the effective locking of the window without any attention to the fastener on the part of the operator.

Another important object of my invention is to provide a sash fastener which is so constructed that the upper and lower sashes will be drawn into intimate contact with one another and held against rattling when the sashes are removed to their extreme closed positions.

A further object of my invention is to provide an automatic window sash fastener which can not be picked from the outside of the window by the insertion of an instrument between the meeting rails of the sashes or shaken loose by manipulating of the sashes.

A further object of my invention is the provision of an automatic window sash fastener embodying a spring pressed locking bolt normally held in a retracted unlocked position by a gravity ball, and a combined keeper and strike plate for engaging and moving the ball to a raised position for permitting the lock bolt to automatically move to a locked position in engagement with said combined keeper and strike plate.

A further object of my invention is to provide an improved window fastener of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:

Figure 1 is a top plan view of my improved sash fastener showing the same in its locked position and applied to the meeting rails of a pair of window sashes.

Figure 2 is a section through the same

taken on the line 2-2 of Figure 1 looking in the direction of the arrows showing the locking bolt in its locked position.

Figure 3 is a view similar to Figure 2 showing the locking bolt in its retracted position for permitting the separation of the sashes.

Figure 4 is a view similar to Figure 3 showing the meeting rails of the sashes separated and illustrating the position of the gravity ball for holding the bolt in its retracted unlocked position.

Figure 5 is a detail perspective view of one section of the improved fastener showing the clamp plate thereof separated from the body portion thereof, and

Figure 6 is a perspective view of the combined keeper and strike plate.

Referring to the drawings in detail, wherein similar reference characters designate corresponding parts throughout the several views, the letter A generally indicates my improved sash fastener and C and B the upper and lower sashes of a window with which the fastener is associated.

The sashes B and C can be of any preferred or ordinary construction and as shown include the meeting rails 10 and 11 respectively.

The improved fastener A comprises the body or casing 15 for the locking bolt or shaft 16 and, as shown, the body or casing 15 is provided with a longitudinal bore for receiving said bolt. The bore is enlarged as at 17 and opens out through the rear end of the body or casing for the reception of an expansion spring 18 which is placed about the said bolt. The spring is retained in position in the enlarged portion 17 of the bore by means of a closure plug 19 which is threaded in said bore and one end of the spring abuts against the same. This closure plug is provided with an axial opening through which the bolt slidably extends and this end of the bolt is provided with a manipulating thumb piece 20.

A cross pin 21, collar or the like is secured to the bolt 16 and the forward end of the spring normally bears against this pin and functions to urge the bolt normally out of the casing or body as clearly shown in Fig-

65

ure 2 of the drawings. The casing or body 15 is provided with laterally extending ears 22 whereby the body or casing may be secured to the top face of the rail 10 by the use of suitable fastening elements 23.

5 The front face of the body or casing is provided with a substantially vertical semi-cylindrical groove 24 which terminates short of the bottom of the body or casing and this 10 groove is adapted to slidably receive a gravity ball or similar member 25 for a purpose, which will be later described. The upper inner edge of the body or casing 15 has secured thereto a clamp plate 26 which projects 15 over said groove and this clamp plate 26 includes a substantial horizontally disposed attaching plate portion 27 and a depending substantially vertically disposed plate portion 28. The inner face of the vertical plate 20 portion 28 is inclined upwardly and inwardly as indicated by the reference character 29 for a purpose, which will also be hereinafter more fully described.

25 The casing, bolt, clamp plate and gravity ball forms one part or section of my improved fastener all of which is carried by the upper rail 10 of the sash B, and in conjunction with this section of the fastener I employ a combined strike plate and keeper 30 section 30 which is carried by the lower rail 11 of the window sash C.

35 The combined strike plate and keeper 30 comprises a base plate section 31 which can be secured to its rail 11 by the use of suitable fastening elements 32, and an upstanding keeper and strike plate member 32. This plate portion 32 is provided with an opening 33 for the reception of the inner end of the lock bolt or shaft 16.

40 The outer face of the plate 32 is beveled upwardly and inwardly as indicated by the reference character 34 for cooperation with the beveled surface 29 of the vertical plate 28.

45 Normally, when the bolt 16 is retracted as shown in Figures 3 and 4 of the drawings the gravity ball 25 drops in front of the bolt 16 and holds the bolt in its retracted position. The window sashes can now be separated as shown in Figure 4 of the drawings.

50 As the sashes are moved to their closed position the combined strike and keeper plate member 32 engages and lifts up the ball 25 above the bolt 16, allowing the spring 18 to automatically move the bolt to its locking position in the opening 33 formed in said combined strike and keeper plate member. As the combined strike and keeper plate member 32 engages the clamp plate member 28 55 the inclined faces thereof have a wedging effect and thus bring the meeting rails 10 and 11 of the sashes toward one another and hold the sashes effectively against rattling.

60 It is obvious from the foregoing that I have provided a simple yet efficient form of

sash fasteners which will move automatically to a locked position when the sashes are moved to their extreme closed position and that the bolt can not be actuated by the insertion of an instrument between the rails 70 10 and 11.

75 Changes in details may be made without departing from the spirit or the scope of this invention:

What I claim as new is:

1. A window sash fastener comprising a body for connection with the upper rail of one sash, a keeper plate for connection with the lower rail of the other sash, a bolt slidably carried by the body for engagement with the keeper plate, and a gravity member carried by the body for movement in front of the bolt upon the retraction thereof for preventing further forward movement thereof, said gravity member when in its lowered position in front of the bolt being in the path of the keeper plate, as and for the purpose specified.

2. A window sash fastener comprising a body for connection with the upper rail of one window sash, a combined strike and keeper plate for rigid connection with the lower rail of the other window sash, a spring pressed bolt slidably carried by the body for engagement with the keeper and strike plate, and a gravity ball slidably carried by the body for movement in front of the bolt when the same is in its retracted position to hold the bolt against return forward movement, the ball when in its lowered position being in the path of the combined strike and keeper plate whereby the same will be raised by said strike and keeper plate when the sashes are moved to their extreme closed position for permitting the automatic return of the bolt to its locked position...

In testimony whereof I affix my signature:
CHARLES H. SUCKEL.
